UNITED STATES PATENT OFFICE.

CHRISTIAN PEDERSEN, OF ST. LOUIS, MISSOURI, ASSIGNOR TO LANDIS MACHINE COMPANY, OF ST. LOUIS, MISSOURI, A CORPORATION OF MISSOURI.

TAKE-UP FOR SEWING-MACHINES.

No. 836,208.

Specification of Letters Patent.

Patented Nov. 20, 1906.

Application filed August 14, 1905. Serial No. 274,113.

To all whom it may concern:

Be it known that I, CHRISTIAN PEDERSEN, a citizen of the United States, residing at St. Louis, Missouri, have invented a certain new and useful Improvement in Take-Ups for Sewing-Machines, of which the following is a full, clear, and exact description, such as will enable others skilled in the art to which it appertains to make and use the same, reference being had to the accompanying drawings, forming part of this specification, in which—

Figure 1 is a side elevational view of the mechanism involved in my invention, part of the frame being illustrated in sections and showing the take-up lever in its uppermost position. Fig. 2 is a similar view showing the take-up lever in its lowermost position. Fig. 3 is a cross-sectional view through the stop-arm. Fig. 4 is a detail elevational view of the take-up lever, and Fig. 5 is a cross-sectional view on line 5 of Fig. 4.

This invention relates to sewing-machines, and particularly to that type known as "wax-thread" sewing-machines, which are used principally for sewing leather.

The object of my invention is to provide a novel form of take-up mechanism for holding the needle-thread taut and also for drawing said thread from the shuttle after the shuttle has passed through the loop therein to form the stitch. I have herein illustrated my novel take-up mechanism in conjunction with the needle and shuttle mechanism of a sewing-machine; but as said needle and shuttle mechanism form no part of my present invention I have not described the same.

The machine herein shown as illustrating the preferred form of my invention is provided with a thread-measurer, which automatically draws from the needle-thread supply just the required amount of thread for forming a stitch; but it should be understood that my take-up mechanism is not limited in its use to a machine provided with a thread-measuring mechanism, but could be used equally well in a machine not having a thread-measurer and provided simply with tension-plates or any suitable form of tension device.

Referring now to the preferred form of my invention as illustrated in the drawings, 1 designates a frame in which is suitably journaled a rotatable shaft 2. The shaft 2 carries a fixed cam 3, which is provided with a

groove 4 of irregular formation and having a portion 5, the radial distance of which with respect to the shaft is considerably greater than the radial distance of the remaining portion of the cam. The reason for this will be fully explained hereinafter.

6 designates a rock-shaft, which is journaled in suitable bearings in the frame, and fixed on said rock-shaft is a depending actuating-arm 7, which is in the form of an elbow-lever, at the angle of which is a roller 8, movable in the groove and coöperating with the cam, whereby a rotation of the shaft 2 will impart an up-and-down movement to the end of the lever distant from the rock-shaft 6.

9 designates a bracket which is suitably supported upon the frame and in a plane below the rock-shaft 6. This bracket carries a journal-bearing 10, in which is mounted a rock-shaft 11, having fixed at one end a crank-arm 12. This crank-arm 12 is provided with an offset, which is movable in a slot 13 in the lower end of the lever 7, so that any movement which is imparted to the lever 7 will be transmitted to the rock-shaft 11 through the arm 12.

14 designates a fixed arm projecting in a direction approximately opposite to the arm 12, and said arm 14 is provided with an adjustable stop or abutment 15, which projects transversely through said arm and which is adapted to engage and move the loosely-mounted take-up arm or lever 16, which is carried by the shaft 11, the adjustability of said stop permitting the degree of movement imparted to said lever 16 to be varied. The heel or rearwardly-projecting end 17 of the lever 16 is provided with a slot 18, adapted to be engaged by a pin 19 on the lever 14, whereby the loose swinging movement of said take-up lever 16 will be limited. The take-up lever 16 is yieldingly connected to a rigid part of the frame by an expandible spring 20, which is fastened to said lever in rear of its fulcrum, so that the normal tendency of the spring will be to depress the forward end of said lever and hold the lower end of the slot 18 in engagement with the pin 19.

The thread leads from the thread-measurer, with which the machine is provided and a portion 21 of which is shown in Figs. 1 and 2 of the drawings, and then passes through the wax-pot under the idler 22, thence over the idler 23 to the roll 24 on the extreme

end of the take-up lever 16, and finally to the needle and shuttle.

In Fig. 1 the take-up mechanism is illustrated as in position after the shuttle has passed through the loop in the thread to lock the needle-thread and shuttle-thread together, and in Fig. 2 it is illustrated as in position after the thread has been drawn from the shuttle to form the stitch. The shuttle mechanism and the take-up mechanism are so correlated with the shaft 2, from which they derive their power, that all of the parts are timed to move in proper sequence. For example, after the shuttle has passed through the loop in the thread and has carried the thread into the position shown in Fig. 1 the relatively deep portion of the cam will be engaging the roller 8, so as to elevate the forward end of the lever 16. Further movement of the main shaft 2 brings the shallow portion of the cam 3 into contact with the roller 8, so as to raise the forward end of said lever 7, and thereby depress the forward end of the take-up lever 16 to draw the thread from the shuttle to form the stitch.

In order to maintain the thread taut at all times, it is necessary that a proper adjustment be made, so as to control the degree of movement of the lever 16, this being provided for by the adjustable stop 15, which engages and moves said lever 16.

As previously stated, it is immaterial so far as the operation of my improved take-up mechanism is concerned whether or not the machine be provided with a thread-measurer, and if the machine were provided simply with tension-plates or any other suitable tension device the operation of the take-up would be the same—namely, to draw the needle-thread from the shuttle and always keep said thread taut.

Having thus described my invention, what I claim as new, and desire to secure by Letters Patent, is—

1. In a sewing-machine, a rock-shaft provided with an arm 14 having an engaging device in its outer end, a take-up lever loosely mounted on said shaft and adapted to be engaged by the device in said arm, coöoperating means on said arm and lever for limiting

their movement relatively to each other, and means for actuating the rock-shaft; substantially as described.

2. In a sewing-machine, a rock-shaft provided with an arm, a take-up lever loosely mounted on said shaft and extending in the same direction as said arm, a device carried by said arm for engaging the take-up lever to impart movement thereto in one direction, means for actuating the rock-shaft, means for governing the position of said take-up lever relatively to said arm, and yielding means for moving the take-up lever away from said arm; substantially as described.

3. In a device of the class described, the combination with a rock-shaft mounted in a stationary bearing and having an arm thereon, a cam-actuated lever for imparting movement to said rock-shaft and in engagement with the arm thereon, a take-up lever loose on said rock-shaft, a second arm on said rock-shaft and provided with a rigid abutment for engaging the take-up lever to move it positively, and means for limiting the free movement of said take-up lever; substantially as described.

4. The combination with a drive-shaft of a sewing-machine, of a cam carried by said shaft, a rock-arm actuated by said cam, a rock-shaft mounted in a stationary bearing and provided at one end with an arm that is in engagement with said rock-arm, a take-up lever loosely mounted on said rock-shaft, a second arm fastened to said rock-shaft and provided with an adjustable abutment which is adapted to engage the take-up lever and move it positively in one direction as said shaft is rocked, and means carried by said second arm and coöoperating with said take-up lever for moving it in the opposite direction back to normal position and also for determining the normal position of said lever; substantially as described.

In testimony whereof I hereunto affix my signature, in the presence of two witnesses, this 11th day of August, 1905.

CHRISTIAN PEDERSEN.
